REVERSING GEAR FOR INTERNAL
COMBUSTION ENGINES

Heinrich Wälti, Winterthur-Wülflingen, Switzerland, assignor to Sulzer Freres Societe Anonyme, Winterthur, Switzerland

Application July 18, 1934, Serial No. 735,816
In Switzerland July 22, 1933

4 Claims. (Cl. 123—41)

This invention relates to oil-burning engines, and especially those for marine duty. It is, more particularly, concerned with the control and reversing gear therefor, and its general object is to provide an improved control for starting, running, and reversing such engines.

A particular object is to provide a control gear in which premature or undesired re-commencement of combustions, invariably the cause of the lag or delay in changing direction from "ahead" to "astern", will be precluded, and by simple means.

In accordance with the present invention the fuel injection pump, after being rendered inoperative preparatory to reversing the direction of rotation of the engine is maintained inoperative until the direction of rotation of the engine actually has taken place. It is then restored to its operative condition by cooperating toothed members, which act as gears, being brought into operative engagement to shift one of said members to a position in which it actuates suitable means to restore the fuel-injection pump to operative condition.

The objects and advantages of the invention will become more manifest from the following description of an illustrative example, taken in conjunction with the accompanying drawing, but the invention is limited in its embodiments only by the scope of the subjoined claims.

In the drawing,

Fig. 1 is a typical schematic lay-out, quite diagrammatic, showing the parts of the control-mechanism in the "full-speed ahead" position;

Fig. 2 is a similar view showing significant parts at the beginning of the "starting astern" position, and

Fig. 3 is a similar view of a more advanced stage of that position.

The mechanism shown in Fig. 1 applied to a cylinder 1, of a Diesel engine includes, among other things, a starting valve 2, a compressed air-pipe 3, and manifold 3', connected thereto, a cam shaft 4 (which changes its direction of rotation when the direction of the engine changes), a reversing lever 5, and a fuel pump 6. The starting valve 2 is reciprocated by the engine in the usual way by conventional means, not shown. The fuel pump 6 includes a piston 7, a fuel-intake valve 8, a fuel-discharge valve 9, and a plunger 10 for reciprocating under and against the intake valve 8.

An arm 11 is provided and mounted for displacement back and forth in the horizontal direction. The member 11 bears a lug 12 and a

longitudinal slot 13. The cam shaft 4 bears a collar 14 fixed thereon adjacent the arm 11, and the collar has two oppositely located lugs 15 thereon, they and the collar being so arranged that they move in the same vertical plane as the lug 12. A small cylinder 17 is provided and suitably mounted below the lever 11. The cylinder contains a piston 16 under the influence of the starting-air, as the cylinder 17 is connected to the pipe 3 by a smaller pipe 18. The piston 16 bears on its upper end a roller 19 which therefore maintains 11 constantly in contact with 14 in all positions.

The lever 11, is connected by slot 13 and pin 24, to a link 20, mounted at its lower end on the fixed pivot 21. The link 20 carries a roller 22 at its upper end, and is movable laterally between two fixed stops 23. A lever 25 is mounted adjacent the roller 22, and bears a cam-face 26. The distal end is pivoted to the starting lever, 5. 20 A plunger 27 is vertically mounted in a fixed member or guide 28 adjacent lever 25, and is supported on it by a roller 29. The plunger terminates at its upper end in a horizontal arm 30. The part 30 engages the plunger 10 of the 25 fuel pump.

A check valve 32 is provided behind the starting valve 2 and is loaded by a spring 33. A piston 34 is mounted on a cylinder 35 and rigidly connected to valve 32. A valve 36 is mounted 30 in a casing 36' and connected on its upper, or inlet, side by a pipe 37 to the starting-air pipe 3. On its discharge side it is connected to the top of cylinder 35 by a pipe 38. An opening 39 exhausts the casing 36' to atmosphere. The valve 35 36 is actuated by a rod 40, which rod is actuated by the extension 41 of member 30. The rod 40 is adapted to be moved up into a constriction 42 when it has pushed the valve 36 upwardly, and then the rod 40 closes off the discharge to 40 atmosphere.

When the lever 5 is brought from the "full speed ahead" position shown in Fig. 1, into the "starting astern" position shown in Fig. 2, in order to reverse the drive, and the direction of 45 the ship, the starting valve 2 is by this movement, in the conventional manner, (not illustrated) opened and set in operation. The valve 8 at the same time is lifted by means of the cam 26 moving over the roller 22. This results in completely shutting off all fuel from the engine, and admitting starting-air into the cylinder. By these means, the engine is first braked to a momentary standstill, and thereafter it is forced to rotate in the reverse direction. 50 55

Until reverse rotation starts, bolt 11 will be held fast, in its extreme left-hand position by the frictional thrust of the ring 14 which is still turning in the direction of the arrow up to the 5 moment of change of direction of rotation. At this moment of change, the ball will be moved by friction toward the right, and finally, when one of the detents 15 bears on the detent 12, it will be forcibly displaced to the right bringing 10 the lever 20 and the roller 22 into the right-hand position shown in Fig. 3. In this way the member 14 effects the movement of the lever 25, and plunger 27, and pin 10 by causing them to fall downwardly under their own weight, whereby the 15 suction valve 8 is released and the fuel-pump again starts to work. Lever 20 and cam 26 constitute a latching mechanism for holding lever 25, plunger 27 and valve-actuating pin 10 in their upper positions as shown in Fig. 2.

20 When the engine is reversed by means of lever 5, the valve 8 and the valve 36 are pushed up simultaneously. Thereupon, piston 34 opens valve 32. Hence, the engine-piston, not shown, (the engine still running by inertia in the former 25 direction of rotation), on up-stroke forces back the starting-air through the valve 32 and valve 2, and can, without producing excessive compression in the starting-air-pipe 3, act as a compressor. The braking action thus produced stops 30 the engine promptly.

Since the engine cylinder can, by the present invention, begin to receive fuel again only from the very moment the direction of rotation of the 35 crankshaft actually begins to change, any premature setting in again of combustion, or "firing", is rendered quite impossible, and this is accomplished by the relatively simple means above described. Also, since at the very moment the direction of rotation changes, the valve 36 is closed, 40 and cylinder 35 is thereby connected again to atmosphere, the valve 32 acts as a check-valve, and any back-fire of the combustion into the starting-air pipe will be made impossible.

Various refinements and modifications in the 45 above construction are considered as being within the scope of this invention; for example, the lever 11, instead of being constantly pressed against the collar 14, may be pressed temporarily or intermittently, and each time only at the very beginning of the reversing operation.

I claim:

1. A reversing gear for internal combustion engines comprising a device for controlling the fuel supply to said engine, a member for actuating said device manually movable to cut off said fuel supply, a latch for holding said member in such position, and means for tripping said latch comprising a circular member adapted to be rotated by the engine, a laterally movable member connected to said latch and held in frictional engagement with said circular member during the operation of reversing the engine, and lugs on said circular member and said laterally movable member adapted to be brought into coaction by the frictional engagement of said circular member and said laterally movable member upon the reversal of rotation of said engine to move said member laterally and trip said latch.

2. A reversing gear for internal combustion engines comprising a device for controlling the fuel supply to said engine, a member for actuating said device manually movable to cut off said fuel supply, a latch for holding said member in such position, and means for tripping said latch

comprising a circular member adapted to be rotated by the engine, a laterally movable member connected to said latch, lugs on said circular member and said laterally movable member adapted to be brought into coaction by the frictional engagement of said circular member and said laterally movable member upon the reversal of rotation of said engine to move said member laterally and trip said latch, and means for bringing said laterally movable member into frictional engagement with said circular member prior to the operation of reversing the engine. 5

3. A reversing gear for internal combustion engines comprising a device for controlling the fuel supply to the engine, a member for actuating said device manually movable to cut off said fuel supply, a cam on said member, a latch for holding said member in such position, means for tripping said latch comprising a circular member adapted to be rotated by the engine, a laterally movable member connected to said latch, lugs on said circular member and said laterally movable member adapted to be brought into coaction by the frictional engagement of said circular member and said laterally movable member upon the reversal of rotation of said engine to move said member laterally and trip said latch, and means for causing said laterally movable member to bear frictionally against said circular member prior to the operation of reversing the engine, 20 said manually movable member being interposed between said latch and a part of the device for controlling the fuel supply to the engine, the cam of said manually movable member, upon operation of said member, to reverse the engine, 25 cooperating with a part of said latch to cause the manually movable member to operate said control device to cut off the supply of fuel to the engine. 30

4. A reversing gear for internal combustion 40 engines comprising a device for controlling the fuel supply to the engine, a member for actuating said device manually movable to cut off said fuel supply, a cam on said member, a latch for holding said member in such position, said latch 45 including a lever having a roller carried thereby which normally engages said manually movable member to assist in guiding the same in its movements, means for tripping said latch comprising a circular member adapted to be rotated by the engine, a laterally movable member connected to said latch, lugs on said circular member and said laterally movable member adapted to be brought into coaction by the frictional engagement of said circular member and said laterally movable 55 member upon the reversal of rotation of the engine to move said member laterally and trip said latch, and means for causing said laterally movable member to bear frictionally against said circular member prior to the operation of reversing the engine, 60 said manually movable member being interposed between said roller and a part of the device for controlling the fuel supply to the engine, said roller by engagement with said cam during movement of the manually movable 65 member to reverse the engine raising said member and causing it to actuate the fuel-controlling device to cut off the supply of fuel to the engine, said latch, when tripped, permitting the manually movable member to fall and the fuel-controlling device to be actuated in the reverse direction to restore fuel delivery to the engine. 70
